(57) **CLAIM**

The ornamental design for an end effector for open vessel sealer, as shown and described.

DESCRIPTION

FIG. 1 is a front, perspective view of an end effector for open vessel sealer in accordance with the present design;

FIG. 2 is a front view of the end effector for open vessel sealer of FIG. 1;

FIG. 3 is a rear view of the end effector for open vessel sealer of FIG. 1;

FIG. 4 is a right side view of the end effector for open vessel sealer of FIG. 1;

FIG. 5 is a left side view of the end effector for open vessel sealer of FIG. 1;

FIG. 6 is a top view of the end effector for open vessel sealer of FIG. 1; and,

FIG. 7 is a bottom view of the end effector for open vessel sealer of FIG. 1.

The broken lines shown in FIGS. 3, 5, and 6 illustrate portions of the end effector for open vessel sealer that form no part of the claimed design.
